UNITED STATES PATENT OFFICE.

FREDERICK C. BAIER, OF CHICAGO, ILLINOIS, ASSIGNOR OF ONE-HALF TO ERNEST B. HOWORKA, OF CHICAGO, ILLINOIS.

MERCURY MOTOR.

1,414,322.

Specification of Letters Patent. Patented Apr. 25, 1922.

Application filed March 13, 1922. Serial No. 543,389.

To all whom it may concern:

Be it known that I, FREDERICK C. BAIER, a citizen of the United States, residing at Chicago, in the county of Cook and State of Illinois, have invented certain new and useful Improvements in Mercury Motors, of which the following is a specification, reference being had therein to the accompanying drawing.

10 This invention relates to motors and more particular to that type of motors in which a fluid is projected under pressure against a wheel of turbine type. My object in producing a motor of the character hereinafter described has been essentially to provide a simple and efficient machine having a wide range of adaptability, which may be operated at a minimum cost and without the disagreeable features found in most motors. In 15 fact, the motor has been designed and tested out for use where economy of operation was a primary object and also with a view to producing a motor at low initial cost and which can be operated where the usually employed fuels are not available.

It has also been my object in constructing this invention to provide a motor which is extremely powerful in proportion to its size and which runs noiselessly and without any 20 disagreeable features such as are attendant upon the use of hydrocarbon motors, steam motors and the like.

In attaining these objects I have also sought and have produced a motor which 25 does not produce any fire hazards and is immune in its action to temperature and atmospheric changes.

Still another object of the invention is the provision of a motor in which the exhaust 30 may be utilized for various purposes where small power may be employed such as running advertising or display novelties.

I have enumerated some of the principal objects of the invention but it will be found 35 upon reading the accompanying specific description in connection with the drawings, forming part of this application, that many other objects are attained not specifically recited hereinbefore.

40 In the drawings:

Figure 1 is a vertical transverse sectional view.

Figure 2 is a side elevation with parts broken away,

Figure 3 is a view in plan with the cover 55 plate and the rotor removed,

Figure 4 is a bottom plan view,

Figure 5 is a detail side elevation with parts broken away and parts in section showing the machine at right angles to the position indicated in Figure 2,

Figure 6 is a detail bottom plan view with the valve cap removed,

Figure 7 is a detail bottom plan view of the rotor, and

Figure 8 is a diagrammatic view illustrating one means of utilizing the exhaust.

Referring more particularly to the drawings, 1 represents a base which is substantially annular in outline and is provided with a depending supporting flange 2 which carries the weight of the motor on a support. The base 1 is provided with a peripheral outstanding flange 3 and an inwardly projecting flange 4 defining a central opening 5 through which the power shaft to be hereinafter described passes.

Arranged around upon the interior of the base and spaced at quartering intervals, as indicated in Figure 3, are suitable cups 6 which are open at their upper ends as shown and which are connected through pipes 7 to a source of air supply through the pipe 8. This pipe 8 is centrally connected to a valve casing 9 by means of a valve cap 10 which is removably secured to the underside of the casing 9 by the screws 11 so that access may be readily had to the valve for purposes of inspection and repair when necessary.

Resting upon the flange 3 and secured thereto by the bolts 12 is the ejector plate 13 having a plurality of nozzles or ejector ports 14 arranged in series and located immediately above each of the cups 6. These openings, as will be noted from an inspection of Figures 1 and 5, have flared lower ends 15 and restricted discharge exits 16 which extend diagonally as shown in Figure 5 so as to direct the fluid discharged therethrough at a tangent to the underface of the rotor as will be hereinafter described.

The pipes 7, as shown in Figures 1 and 2, have transverse openings in their ends through which pass the hollow coupling or connecting members 17 each having a port 105 communicating with the opening in the pipe and a clamping heading 18 at their inner ends which is passed through and serves to

clamp the flexible bags or tubes 18^a to the bottom of the cups 6 so as to prevent any escape of air at this point. The outer ends of the members 17 are threaded to receive the clamp nuts 19 which serve to draw the heads 18 tightly against the bag as will be readily understood.

In Figure 1 I have shown the bags partially inflated and in Figure 2 they are completely deflated and when in this latter position the cups are practically filled with mercury so that upon inflation of the bag the mercury is discharged through the ports 14 against the blades of the rotor, which is generally indicated at 20.

This rotor is substantially disc-like in outline and is provided with an inclined upper surface and at its periphery with a weighted margin 21 so that it acts in the nature of a fly wheel when placed in motion thus overcoming any inertia during inactive periods of the mercury against its vanes. The weight 21 is annular in outline but is cut-away at intervals to produce channels 22 which are provided in case the mercury should be splashed on top of the rotor it could readily gain access to the plate 13 and flow back into the cups 6 as will be readily understood. The lower face of the rotor is provided with two depending annular flanges 23 and 24 between which are arranged a series of vanes or turbine blades 25 extending radially and constructed and formed as indicated in Figure 5 so as to form pockets into which the mercury is discharged.

Over the ejector plate and secured to the flanges 3 by the bolts 12 is a cap plate or cover 26 which is provided in its center with a bearing boss 27 having one element of a ball bearing 28 secured therein. This element, which is preferably the cup of the bearing, also holds in position a packing 29 which retains the lubricant around the bearing in an effective manner. Passing through the boss 27 is the driving shaft 30 which has keyed to it the rotor 20 and which carries the opposite member 31 of the upper ball bearing. The shaft 30 also carries a cone 32 of the lower ball bearing, the cup 33 of this bearing being held in a central boss which is formed integral with the ejector plate as is clearly shown in Figure 1.

The lower end of the drive shaft 30 is bifurcated, as shown at 34, to receive the extended tenon 35 formed on the upper end of the valve stem 36. This valve stem passes through a packing 37 placed in the upper end of the valve casing 9 and carries at its lower end the valve 38 which is retained within the valve casing by the cap 10 and has bearing upon its upper surface against a series of balls or anti-friction members 39 which are provided to take up thrust produced by the pressure of the air

thereon. This valve is provided with a pair of diametrically opposite ports 40 and 41 which communicate, as will be readily understood, with diametrically opposite pipes 7 when in the proper position.

As will be readily seen from an inspection of Figure 6 when the ports 40 and 41 get in communication with diametrically opposite pipes 7 the air from the pipe 8 will pass through the pipes 7 into the tubes or bags 18 of opposite cups 6. These bags being inflated simultaneously the mercury resting upon each will be projected forcibly through the discharge ports 14 and projected against the blades or vanes of the rotor which starts the rotation of this member. The rotor being keyed to the shaft 30 and this shaft in turn being keyed to the valve stem the valve is caused to rotate and thus alternately feed air from the source of air supply to opposite pairs of cups so as to displace the mercury above the resilient bags or tubes therein.

The valve 38 is also provided with a pair of ports 42 and 43 arranged at substantially diametrically opposite points and which connect with a common exhaust port 44 leading upwardly through the valve stem 36 and communicating with a similar port 45 in the drive shaft 30. When the ports 40 and 41 are in register with diametrically opposite pipes the ports 42 and 43 are in register with the pipes which are positioned at 90° thereto. In other words, when one diametrically opposite pair of pockets is receiving air under pressure from the pipe 8 the other diametrically opposite pair is exhausting the air from their then connected pockets by reason of the weight of the mercury operating to collapse the bags or tubes 18 therein.

In Figure 6 the ports 40 and 41 are shown between the diametrically opposite pairs of pipes and with the port 42 just coming into registry with one of the pipes 7. In this position the air under pressure in the bag or tube which is connected with that particular pipe will be exhausted through the port 42 and the port 45, to be utilized in operating any suitable mechanism. When the port 42 is fully in registry with one of the pipes the port 40 will start to register with another similar pipe at a 90° angle thereto, and then the port 43 will come into registry with a pipe 7 diametrically opposite to that which is then registering with the port 42. From this it will be noticed that the power stroke of diametrically opposite pistons overlaps that of the exhaust stroke of those pistons at right angles thereto, so that there is a continuous and positive engagement of the fluid bodies with the rotor at all times.

It will be noticed from an inspection of Figure 1 that the ejector plate is provided

with a peripheral upstanding flange 46 which projects up into and fits tightly against the inner side of the depending annular flange of the cover or cap plate so that any mercury which may accidentally gain access to the space between the flange 24 of the rotor and the cover 26 will be conducted back to the openings 14.

In order that the rotor may be shipped 10 from place to place without its mercury content thereby eliminating much additional weight and decreasing the shipping cost I provide means whereby each pocket may be filled with the required amount of mercury 15 by drilling a hole through the depending flange of the cover and through the flange 46 of the injector plate and then closing this opening by a suitable screw threaded plug 47.

20 As will be readily appreciated from what has gone before the tubes or bags 18 in diametrically opposite cups are alternately inflated by air pressure and alternately deflated by the weight of the mercury flowing back into the cup so that there is produced in the port 45 an intermittent exhaust. This exhaust may be utilized in various different fashions such as, for instance, that disclosed in Figure 8 wherein the upper end 25 of the shaft 30 has secured thereto a disc 48 rotatable therewith and capable of supporting a number of articles of merchandise to be displayed. The shaft in this instance is also provided with a cylinder 49 in which 30 a piston 50 is mounted. This piston is provided at its upper end with a contact 51 which is adapted to be brought into engagement with each exhaust movement of the bags 18 with a contact 52 of a lamp circuit, generally indicated at 53, and including a source of current. The cylinder is provided with an exhaust port 54 which allows the air in the cylinder to exhaust after it has operated the piston. When the air has been 35 entirely exhausted from the cylinder 49 through the port 54 the piston 50 drops and separates the contact and thus extinguishes the light. Thus it will be seen that the articles of display rotating with the shaft 40 45 50 55 30 are intermittently illuminated and then thrown into darkness.

Figure 8 simply illustrates one form or one method of utilizing the exhaust air. Many others may be devised and I have contemplated many uses for this exhaust which have not been illustrated herein, among which is the inflation of flexible figures or the operation of dancing toys, etc.

In Figure 1 I have shown a pulley 55 connected to the shaft 30 which may be belted to any machinery which it is desired to operate and in Figure 5 I have shown removably keyed to the upper end of the shaft a phonograph disc. This simply illustrates two ways in which the power of the

motor may be utilized but it will, of course, be understood that this is a prime mover and the power taken off of the shaft 30 may be utilized in any way which is found desirable.

It must also be noted that although the machine illustrated herein is for small work that by increasing the size of the machine and increasing the number of fluid pistons employed the power may be readily increased and the capacity of the machine enlarged.

In using the motor for advertising work or for driving a phonograph record-supporting disc, I preferably connect the pipe 80 8 with a storage tank of air which may be charged by an ordinary hand pump or where a great number of motors are used in any one community charged tanks could be substituted for depleted ones in a manner 85 which is well known and which has been successfully adopted in the sale of oxygen and illuminating gas.

It will be noticed that by projecting the mercury against the underface of the rotor 90 as distinguished from projecting a fluid on top of the rotor a great deal of the weight of the rotor is taken off the bearings and the weight of the fluid against the rotor is entirely eliminated so that the rotor operates much freer and with an entire elimination of noises and where the exhaust is employed for some purpose similar to that illustrated in Figure 8 the sound of the exhaust when the motor is in operation can 100 hardly be heard. It will thus be seen that I have not only provided a very efficient and noiseless motor but one in which the cost of maintenance of operation is reduced to a minimum. In the claims I shall refer to 105 the tubes or bags 18 as a flexible piston and to the mercury body as a fluid piston, but I do not wish to be limited in any sense to a fluid piston of mercury as any fluid with sufficient specific gravity to rapidly return 110 to the pockets when the pressure is released from beneath the same and to deflate the tube or bags can be employed equally well for the purpose.

I claim:

1. A motor comprising a rotor having vanes, a fluid body, and a source of continuous pressure intermittently controlled for projecting said fluid body against said vanes.

2. A motor comprising a rotor having vanes, separated fluid bodies, and a source of continuous pressure intermittently controlled for projecting said bodies against said vanes.

3. A motor comprising a rotor operating 125 in a horizontal plane having vanes on its underside, separated fluid bodies, and means for intermittently projecting said bodies against said vanes.

4. A motor comprising a rotor having 130

- fluid receiving vanes, fluid bodies adapted to be projected against said vanes, fluid means for projecting the fluid bodies, said fluid means being of a lesser specific gravity than the fluid body and operating under a source of continuous pressure.
5. A motor comprising a rotating member, a mercury body, a source of fluid under pressure, a flexible piston supporting the mercury body, and means for admitting the fluid under pressure to the side of the flexible piston opposite the mercury body whereby the mercury body is projected to operate the rotating member.
- 10 6. A motor comprising a vaned rotor, separated flexible pistons, mercury bodies supported upon said flexible pistons, a source of fluid under pressure, and means for intermittently admitting the source of pressure to the side of the flexible pistons opposite to the mercury body whereby the mercury body is projected against the rotor.
- 15 7. A motor comprising a vaned rotor, a plurality of flexible pistons, separated mercury bodies resting upon said pistons, a source of fluid under pressure, and means actuated by the rotor for admitting said fluid to the sides of the piston opposite the mercury bodies for projecting the mercury bodies against the vanes of the rotor.
- 20 8. A motor comprising a vaned rotor, a plurality of flexible pistons, fluid bodies supported by the flexible pistons, a source of fluid under pressure adapted to operate the flexible pistons, and means actuated by the rotor for intermittently causing the fluid under pressure to operate the flexible pistons.
- 25 9. A motor comprising fluid pistons and flexible pistons, means for raising the flexible pistons to displace the fluid pistons, said fluid pistons adapted to return the flexible pistons to initial position when the means for actuating the flexible pistons is inactive.
- 30 10. A motor comprising fluid pistons and flexible pistons, means for raising the flexible pistons to displace the fluid pistons, said fluid pistons adapted to return the flexible pistons to initial position when the means for actuating the flexible pistons is inactive, a rotor actuated by the displacement of the

fluid piston, and means actuated by the rotor for controlling the flexible piston operating means.

11. A motor comprising fluid pistons and flexible pistons, means for raising the flexible pistons to displace the fluid pistons, said fluid pistons adapted to return the flexible pistons to initial position when the means for actuating the flexible pistons is inactive, and a rotating member operated upon displacement of the fluid pistons.

12. A motor comprising flexible pistons, fluid pistons supported thereon, a source of fluid under pressure adapted to elevate the flexible pistons and displace the fluid pistons, a rotor actuated by the displacement of the fluid pistons, a source of fluid pressure, and a valve actuated by the rotor for controlling the admission of the fluid under pressure to the flexible pistons.

13. A motor comprising flexible pistons, a source of fluid pressure connected to one side of the pistons, fluid pistons supported by the flexible pistons, and adapted to be displaced upon movement of the flexible pistons, a rotor actuated by the displacement of the fluid pistons, said fluid pistons adapted to return the flexible pistons to normal position upon disconnection of the source of fluid pressure from said flexible pistons, and means for conducting away the exhausted fluid when the flexible pistons are returned to normal position.

14. A motor comprising a plurality of flexible pistons, a source of air under pressure adapted to be connected to one of the flexible pistons, fluid pistons supported by the flexible pistons and adapted to be displaced by movement of said flexible pistons, a rotor actuated by the displacement of the fluid pistons, a valve actuated by the rotor for controlling the admission of air to the flexible pistons, said fluid pistons adapted to return the flexible pistons to normal position when the air pressure is disconnected therefrom, and means for conducting away the air exhausted by the return of the flexible pistons.

In testimony whereof I affix my signature,
FREDERICK C. BAIER.
